UNITED STATES PATENT OFFICE.

FRANK JAGER, OF CHICAGO, ILLINOIS.

METAL CAR-ROOF.

1,121,842.

Specification of Letters Patent. Patented Dec. 22, 1914.

Application filed February 3, 1913. Serial No. 745,821.

To all whom it may concern:

Be it known that I, FRANK JAGER, a citizen of the United States, and residing at Chicago, county of Cook, and State of Illinois, have invented certain new and useful Improvements in Metal Car-Roofs, of which the following is a specification.

My invention relates generally to roofing and has reference more particularly to improvements in metallic roofing plates in a railway freight car.

The principal object of my invention is to provide a novel roofing construction for a freight car comprising a series of metallic plates adapted to be secured to car frame members in a manner more fully described hereinafter, whereby one or more of the series of plates may be readily removed for purposes of repair or replacement without interference with or unfastening the other plates in the series. Another object of my invention is the provision of novel means in metallic roofing plates whereby the fastenings provided to secure them to car members do not pass through outside sheets, and is thereby designed to prevent leakage of water around bolt heads, ordinarily provided to pass through outside roof coverings; and a further object is to provide an improved metallic roofing comprising a series of sheets having water tight joints at meeting edges, which at the same time are designed to permit sufficient play of the plates therein to allow for twisting or weaving of car members resulting from shock or jar.

These, together with such other objects as may hereinafter appear, or are incident to my invention, I attain by means of a construction illustrated in preferred form in the accompanying drawings, wherein:

Figure 1 is a plan view of a portion of a car roof embodying my invention; a portion of the roofing being broken away to better illustrate certain parts.

Figure 2 is a transverse sectional view through the roof shown in Figure 1, and Figure 3 is a side elevation of Figure 2.

Figure 3^a is a longitudinal section of a portion of the roof on a line adjacent to the ridge pole, and Figure 4 is a similar view but showing one of the plates given angular movement for purposes of disengagement.

Figure 5 is a diagrammatic illustration of one of the metal blanks which ultimately form one of the roofing plates A; and Figure 6 represents a view in perspective of one

of the plates. Figure 7 is a perspective of a portion of the plate taken from the left hand side of Figure 6.

Figure 8 is an enlarged sectional view illustrating the means for securing the saddle to the ridge pole.

In this class of car roofs, outer sheets of metal are usually employed and depended upon to make the roof water-tight. In fastening these sheets to car frame members, bolts or similar clamping elements are ordinarily used for purposes of attaching the sheets to the car frame members which support them, the bolts necessarily passing through the outer covering. Consequently as these bolts frequently work loose, water collects around the bolt heads or nuts, and as a result leakage into the car occurs. To overcome this, numerous expedients have been devised involving the use of a number of detached or complicated parts which have many disadvantages incident to their use, among which may be mentioned the tendency of such parts working loose and becoming lost, and also the great addition to the initial cost and subsequent maintenance of these roofs.

In maintaining these roofs, it is often necessary to remove a damaged or leaky sheet for the replacement of another. Carrying this out frequently necessitates the removal of the entire series of roofing plates, by reason of the fact that some of these attaching parts coöperate with other parts of like character, or with other plates, or with car frame members, so that one plate cannot be removed without removing others.

With this in view, it is my purpose to provide a series of roofing plates having an inner depending flange formed integrally with the plates for attachment to supporting frame members, and adapted to hold the joints forming the playroom at meeting edges of plates firmly in place, any one or more of the plates being readily removable without interference with other plates.

In describing my invention, the numeral 10 indicates the carlines, 11 the ridge pole, 12 the side plates, 13 the car siding, and 14 the fascia, forming part of the car frame supporting the series of metallic roofing plates A running from one of the eaves to the ridge pole 11 and the series of metallic roofing plates B running to the ridge pole 110 from the other eave; their meeting side edges being interlocked and meeting ends

overlapped at the ridge, substantially as shown in the drawings.

Each of the plates A is entirely formed and pressed from a metal blank, as shown 5 in Figure 5 wherein the dotted lines indicate the line of bend, and is united to its adjacent sheets by a water-tight joint C comprising a broad rebent double fold 15 formed from the side edge of one sheet, 10 and a struck-up marginal flange 16 formed from the side edge of the adjacent sheet. It will thus be seen that each sheet A is provided with a flange 16 and a double fold 15, the interior portion of the latter 15 which receives the flange 16 of the adjacent sheet is of a breadth sufficient to provide ample play therein for that sheet, and to permit its removal when given angular movement to a position substantially at 20 right-angles to the roof.

The web of each sheet is pressed short of its edge to form the double fold 15, the marginal web being bent horizontally inward a short distance to provide an integral 25 extension 17, which rests upon part of the upper surface of a carline 10 bringing the joint C centrally thereof; the web further continuing downwardly to form a depending flange 18 provided with slotted holes 19 30 to receive bolts 20 for attachment to one of the sides of the carline 10. The plate A is preferably furnished with a down-turned flange 21 overhanging but spaced a short distance away from the fascia to permit 35 such transverse adjustment or play of the plates as afforded by the slotted holes 19. To prevent rain beating up into the open face of the joint at the eave, a depending hood 22 is formed from a projecting web portion of the blank and folded down as shown in the drawings to close the open face. At the end of the plate where 40 it rests upon the ridge, I provide a rebent margin 23 having projecting lugs 23^a and 45 23^b at its ends, which are bent inwardly to engage with the flange 16 and the double fold 15, thus aiding in retaining those members in position when subjected to pressure.

The plates B have similar joints as the 50 plates A, and differ therefrom only in the struck up flange 24 at its meeting end which is adapted to be received within the rebent margin 23 of sheet A. It will be seen that I am enabled by my invention to furnish a 55 roof of comparatively small cost as the separate metal plates of the roof can be cheaply made and readily assembled in position to form the car roof.

The numeral 25 represents the saddles 60 which straddle and cover the joints C and rebent margins 23 at the points where they converge centrally of the ridge pole, this convergence allowing a clear opening at these points for passing the bolts 26 through 65 the ridge pole and then through each saddle;

the saddle being clamped upon the joints and margins by means of a nut 27 screwed down on the bolt 26.

The nut 27 is received in a recess 28 and is covered by a cap 29 whose upper surface is 70 flush with the upper face of the saddle. Bridging between adjacent saddles are short sections of run boards 30 which retain the caps 29 in place, and effectually prevent leakage past the nut and bolt into the car. 75

To remove one of the sheets A, its inner flange is uncoupled from within the car, the saddle resting upon its double fold 15 and its section of running board is removed, then the sheet is given upward movement on 80 an arc with the base of its flange 16 forming the axis of this movement until the sheet may be slipped out. A portion of the rebent margin 23 of the plate A is cut away at the said axial line, thus providing a clearance 85 31, designed to prevent possible binding on the struck up flange 24 of the adjacent sheet B. If a sheet B is to be taken out, the removal of the adjacent sheet A readily permits this to be done, without uncoupling additional saddles or sections as the axis of movement of both sheets A and B is in the same axial line. To prevent any possibility of binding in the initial movement of either 90 of the sheets, the side of the saddle nearest 95 the axial line may be slightly beveled if desired as at 32.

From the foregoing, it will be apparent that the entire construction is simple and economical, comprising the plates, saddles 100 and run boards, wherein the fastening means are entirely inclosed and so arranged as to permit ready removal of such plates as may be required. Furthermore the joints between sheets are water-tight and yet are loose 105 enough to permit the necessary play of the sheets. Other advantages will readily appear to those skilled in the art.

Having thus described my invention and 110 illustrated its use what I claim as new and desire to secure by Letters Patent is the following:

1. In a car roof, the combination with a carline, of a metallic roof sheet provided at one side thereof with a depending perforated sheet-attaching-flange formed to project into the car, a portion of said flange being bent inwardly against the body portion of the sheet to form a substantially horizontal bearing surface adapted to bear upon 115 the upper face of the carline, and fastening means engaging said perforated flange for detachably connecting the sheet to the carline.

2. In a car roof, the combination with a 120 carline, of a plurality of metallic roof sheets disposed in the same plane and adapted to be united together at their side edges by watertight, loose, high-standing joints composed each of a struck up flange on the 125

side edge of one sheet and a double folded portion of inverted U shape on the side edge of the adjacent sheet, said double folded portion being adapted to fit over the struck up flange of the other sheet and provided with an integral sheet-attaching-flange depending from the joint for attachment to the carline, substantially as described.

3. In a car roof, the combination with a carline, of a plurality of metallic roof sheets disposed in the same plane and adapted to be united together at their side edges by high-standing joints composed each of a struck up flange on the side edge of one sheet and a double folded portion of inverted U shape on the side edge of the adjacent sheet, said double folded portion being adapted to fit over the struck up flange of the other sheet, and having a depending sheet-attaching-flange bent inwardly and downwardly away from the joint to rest up against the upper face and one side of the carline.

4. In a car roof, the combination with a carline, of a metallic roof sheet provided at one side thereof with a depending web portion formed with an elongated slot and adapted to project into the car adjacent the carline, and a bolt loosely engaging said slot for connecting the sheet to the carline, the bottom edge of said sheet being flanged down over the car siding and spaced away therefrom to constitute a clearance therebetween, all so constructed and arranged as to permit limited relative play of the sheet in a horizontal plane, substantially as described.

5. In a car roof, the combination of a pair of adjacently positioned metallic roof sheets having their body portions disposed in the same plane, each having a struck up flange at one side edge and a bent folded portion at the other side edge adapted to fit over the struck up flange of the adjacent roof sheet to form a high-standing joint therewith, the bent folded portion of one of the sheets being provided with a depending

inner flange adapted to project into the car, and a bolt engaging the depending flange for detachably connecting the plate to the car, all so constructed and arranged that uncoupling of the bolt permits the withdrawal of the sheet sidewise away from its joint with the other of the plates, substantially as described.

6. As an article of manufacture, a metallic roof sheet formed from a single metal blank and composed of a body portion having flanged top and bottom edges, and provided at one side edge with a struck up flange and at its other side edge with a double folded rebent portion, said rebent portion having an attaching-flange bent inwardly and downwardly therefrom to depend from the body portion at one side of the said rebent portion.

7. In a car roof, the combination with a removable saddle and a run board section, of an outer roof covering comprising metallic roof sheets arranged in series to extend between the ridge and the eaves, the sheets being adapted to be united together at their side edges by high standing joints composed each of a struck-up flange on the side edge of one sheet and a folded portion on the side edge of the adjacent sheet, the meeting ends of said sheets being lapped over at the ridge, a sheet-attaching flange formed integrally with the sheet and projecting into the car, and means passing through said flange for detachably connecting the sheet to the car, uncoupling of which permits the withdrawal of the sheet sidewise away from its joint with the adjacent plate on removal of the saddle and the run board section, substantially as described.

In testimony whereof I have hereunto signed my name in the presence of the subscribed witnesses.

FRANK JAGER.
